POWER-DRIVEN CONVEYER

Joseph M. O'Malley, Worcester, Mass., assignor to
 Morgan Construction Company, Worcester,
 Mass., a corporation of Massachusetts

Application March 6, 1939, Serial No. 260,121

4 Claims. (Cl. 198—127)

This invention relates to power-driven conveyers, and more particularly to conveyers of the type having a series of rotating rollers arranged to move elongated bars of material in a longitudinal direction.

Conveyers of this general construction are often used for transporting hot metal bars in rolling mills, and in many cases provision is made for discharging the bars laterally from the rollers 10 on to cooling beds located at one or both sides of the conveyer. It has been proposed heretofore to drive the rollers electrically, but the prior constructions have been complicated and expensive, with a tendency toward overheating of the electrical circuits. Furthermore, the construction of these prior electrically driven rollers has been such as to require the use of yokes or similar devices for supporting the rollers, particularly when they are installed in conveyers having provision 20 for effecting lateral discharge of the bars by an angular displacement of the axes of the rollers. When the conveyer is associated with a double cooling bed, it is a common practice to provide two parallel lines of travel for the bars, with a 25 switching device arranged to direct the bars to the respective lines alternately. This has certain disadvantages, particularly when the bars are relatively wide, for such bars cannot be bent readily in lateral directions.

It is accordingly one object of the invention to provide a comparatively simple and inexpensive electrically driven roller which can be operated continuously without overheating.

It is a further object of the invention to provide an electrically driven roller which can be supported in a simple manner and which is particularly adapted for use in conveyers having provision for discharging bars laterally therefrom.

It is a further object of the invention to provide a comparatively simple and inexpensive conveyor arranged to move elongated bars of material longitudinally in a single line and to effect their lateral discharge to either side as desired.

With these and other objects in view, as will be apparent to those skilled in the art, the invention resides in the combination of parts set forth in the specification and covered by the 50 claims appended hereto.

Referring to the drawings illustrating one embodiment of the invention and in which like reference numerals indicate like parts,

Fig. 1 is a fragmentary plan view of a power-driven roller conveyer, the portion at the left

end of the figure being shown in section on the line 1—1 of Fig. 2;

Fig. 2 is an enlarged view in section on the line 2—2 of Fig. 1;

Fig. 3 is an enlarged view in section on the line 3—3 of Fig. 2;

Fig. 4 is a section on the line 4—4 of Fig. 2;

Fig. 5 is a view similar to Fig. 4 but showing the parts in position to discharge a bar laterally; and

Fig. 6 is a detail of a supporting member for a roller.

The embodiment illustrated comprises a series of spaced power-driven conveyer rollers 10 arranged with their upper or stock-supporting surfaces in horizontal alignment. These rollers serve to convey elongated bars of stock in a longitudinal direction as indicated by the arrow in Fig. 1, the axes of the rollers being horizontal and transverse to the line of stock travel. On each side of the line of conveyer rollers there is provided a longitudinally extending receiving trough 11, these troughs forming a part of a double cooling bed, which may be of any suitable construction. In order to support the bars of stock between the rollers and prevent excessive sagging of these bars, suitable horizontal plates 12 are provided with their upper surfaces located slightly lower than the tops of the rollers.

As shown particularly in Fig. 3, each roller 10 is formed with two axially-aligned parts or elements each of which comprises an annular flange or rim 14, a central hub 15, and radial spokes 16 connecting the hub to the flange. The adjacent inner edges of the flanges 14 are separated by a narrow annular space or slot 17. The hubs 15 are mounted on the opposite ends of a normally horizontal shaft 19 forming a part of an electric motor 20 which is enclosed by the flanges 14. This shaft 19 is rotatably supported in suitable bearings 21 in the two end-frames 22 of the motor. On the central portion of the shaft there is mounted a rotor 24 which is surrounded by the usual stator 25. The end-frames 22 are connected by bolts 26. Between the two end-frames 22 there is mounted a curved or arcuate member 28 which extends partially around the outside of the stator 25 and is held in place by the clamping action of the bolts 26. This member is formed on its outer surface with a narrow rib 29 which extends into the space 17 between the flanges 14 and at one point projects outwardly through this space to connect with an enlargement or boss 30. This boss provides the means for supporting the motor in the proper position in the conveyer.

The member 28 is preferably formed with a gap 32 at the bottom (Fig. 6) so that when the parts are assembled a narrow opening will be provided between the flanges 14. The electrical leads (not shown) to the motor 20 may pass through this opening, and it may also be used for the admission of air to cool the motor. The desired air circulation may be brought about by forming the spokes 16 at an angle with the axis 10 of rotation as indicated in Fig. 2, so that they will act as vanes or propeller blades to blow air outwardly from the ends of the roller. If suitable side guides are provided, the rollers 10 may be made cylindrical in shape, the guides 15 being depended upon to maintain the bars in the proper line of travel. However, in the embodiment illustrated I have shown no side guides, since they complicate the problem of discharging the bars laterally from the rollers, and I 20 have formed the flanges 14 with tapered or frusto-conical outer surfaces which converge toward the centers of the rollers. This construction will be effective to prevent lateral deviation of the bars from the desired line. 25 The discharge of the bars laterally from the rollers into the troughs 11 is preferably brought about by tipping the rollers and the plates 12 to one side or the other as desired. For this purpose each boss 30 is secured to one end of a horizontal shaft 34 which extends at right angles with the axis of the roller, each shaft 34 being rotatably mounted in a pair of bearings 35 (Fig. 2) 30 on a bracket 36. The entire series of brackets is mounted on a pair of spaced parallel beams 38 which extend longitudinally of the conveyer. The beams 38 are supported by a series of transverse frame members 39. Each plate 12 is carried by a supporting hub 40 therebeneath which is secured to the adjacent shaft 34. An arm 42 35 extends downwardly from each shaft 34, and each arm carries at its lower end a roller 43 which is positioned within a slot 44 formed in an arm 46. These arms 46 extend upwardly from a longitudinally positioned control shaft 47 carried in bearings 48 on the frame members 39. By turning the control shaft 47 to one side or the other as desired, the rollers 10 and plates 12 may be tilted laterally, as shown for example in Fig. 5, causing the bar of stock to slide by gravity into 40 the trough 11 adjacent the depressed ends of the rollers. It will be noted that the ends of the rollers are formed with spherical surfaces to reduce the clearance space required between the rollers and the troughs 11. 45 The operation of the invention will now be apparent from the above disclosure. Upon energization of the motors 20, the shafts 19 and rollers 10 will be rotated, and the bars of material will be transported longitudinally on the upper surfaces of the rollers. The spokes 16 will act as fan blades to draw cooling air upwardly through the gap 32 in the bottom of each member 28 and discharge this air outwardly from the ends of the rollers. So long as the axes of the rollers 10 are 50 horizontal the bars of material will remain on the centers of the rollers, bridging the narrow slot 17, because of the slight tapering of the flanges 14. By turning the control shaft 47 slightly in one di-

rection or the other, the rollers 10 and plates 12 will be tilted to one side, and the bar will be discharged laterally by gravity into one of the troughs 11.

The conveyer is comparatively simple and inexpensive. It is well adapted for use as a hot run-out from a rolling mill to a double or single cooling bed. No switching device is required, and there is no lateral bending of the bars, since they travel in a direct line along the centers of the 10 rollers until they are discharged therefrom.

Having thus described my invention, what I claim as new and desire to secure by Letters Patent is:

1. A power-driven conveyer for elongated bars 15 of material comprising an electric motor having a normally horizontal rotatable shaft, rotatable elements secured to the opposite ends of the shaft and having annular flanges which extend toward each other in surrounding relation to the motor, the adjacent edges of the flanges being separated by a narrow slot, means extending inwardly through the slot to provide a support for the motor, a substantially horizontal shaft connected to the supporting means and extending at right angles with the motor axis, and means to oscillate the last-mentioned shaft and thereby effect lateral discharge of a bar. 20 25

2. A power-driven conveyer comprising an electric motor having a normally horizontal rotatable 30 shaft, rotatable elements secured to the opposite ends of the shaft and having annular flanges which extend toward each other in surrounding relation to the motor, the adjacent edges of the flanges being separated by a narrow slot, means 35 extending inwardly through the slot to provide a support for the motor, and means extending upwardly from the motor to provide a closure for the upper portion of the slot.

3. A power-driven conveyer comprising an electric motor having a normally horizontal rotatable shaft, rotatable elements secured to the opposite ends of the shaft and having annular flanges which extend toward each other in surrounding relation to the motor, the adjacent edges of the flanges being separated by a narrow slot, means 45 extending inwardly through the slot to provide a support for the motor, and a rib extending upwardly from the motor into the upper portion of the slot to provide a closure therefor. 50

4. A power-driven conveyer for elongated bars of material comprising an electric motor having a normally horizontal rotatable shaft, rotatable elements secured to the opposite ends of the shaft and having annular flanges which extend toward each other in surrounding relation to the motor, the adjacent edges of the flanges being separated by a narrow slot, means extending inwardly through the slot to provide a support for the motor, a substantially horizontal shaft connected to the supporting means and extending at right angles with the motor axis, a substantially horizontal plate located adjacent the rotatable elements to prevent sagging of the bars and connected to the last-mentioned shaft, and means to oscillate the last-mentioned shaft and thereby effect lateral discharge of a bar. 55 60 65

JOSEPH M. O'MALLEY.
